TYPEWRITING MACHINE

William F. Helmond, West Hartford, Conn., assignor to Underwood Elliott Fisher Company, New York, N. Y., a corporation of Delaware

Application December 30, 1938, Serial No. 248,502

9 Claims. (Cl. 197—178)

This invention relates to typewriting machines and with regard to certain more specific features thereof to tabulating mechanism and more particularly denominational tabulator mechanism. 5 The invention, in certain respects, may be embodied in a manually operated device. In other respects the invention is especially suited to completion of the operations from a source of electric or other power after the cycle has been 10 initiated by manual operation of a key.

The present invention is in the nature of an improvement on the one shown and described in my copending application Serial No. 248,503, filed December 30, 1938, and it has for one of 15 its objects the further simplification of the mechanism therein shown.

A general object of the invention is to employ a power agency to set a selected stop in position to arrest a typewriter carriage, upon the selection of the stop by a light touch upon a key. 20 The power is also employed to release the carriage from its escapement control and to apply and hold a brake upon the carriage movement. Upon completion of the carriage movement to 25 stop position the majority of the parts of the mechanism are automatically restored to normal position. These functions broadly are accomplished by the device shown and described in my said copending application but in the present 30 mechanism the devices by which denominational selection and primary setting of the parts is effected are much simpler, less expensive to manufacture, and the power is immediately disconnected upon release of the key without waiting 35 for the completion of the tabulating operation.

Although in the specific embodiment of the invention herein shown and described an intermittently energized motor is used, it will be obvious that the invention is as well suited to a 40 continuously running motor.

In the drawings—

Fig. 1 is a view in perspective of a denominational tabulator mechanism embodying the present improvements.

Fig. 2 is a view in fore-and-aft cross section of the mechanism shown in Fig. 1.

Fig. 3 is a view of the tabulator magazine and related parts as viewed from the front of the machine.

Fig. 4 is a view of the clutch mechanism with the clutch open.

Fig. 5 is a view of the clutch mechanism with the clutch closed.

Fig. 6 is a diagrammatic view showing the 55 positions assumed by the parts upon depression

of a key and before the power has been rendered effective.

Fig. 7 is a view similar to Fig. 6 showing the parts in the positions which they assume after the power has been applied and before the carriage has banked against the set stop. 5

Fig. 8 is a view similar to Figs. 6 and 7 showing the positions assumed by the parts during the banking operation and just prior to the return of the parts under their influencing springs. 10

Fig. 9 is a fragmentary view showing the brake assembly.

Fig. 10 is a detail of the rocker upon which the brake shoe is mounted.

Referring now more particularly to the drawings, a typewriter frame is indicated generally at 20. At the rear of the frame a magazine or tabulator frame 21 is suitably secured. The magazine is desirably a casting supplemented by a plate 22 at the top having slots 23 for slidably 20 receiving the upper ends of tabulator stop reeds or blades 24.

The magazine 21 has a lower transverse web 25, a middle transverse web 26 and an attached comb plate 27 above the web 26 which is angle 25 shaped and provided with opposite side ears 28 which support a pin 30. Web 25 is comb slotted as indicated at 31 and web 26 is comb slotted as indicated at 32 for purposes of guiding certain of the parts, as will more particularly herein- 30 after appear.

One of a series of denominational tabulator key levers is indicated at 33 pivoted at 34 on a bracket 35 secured to the frame of the machine. The forward ends of the key levers are guided in 35 a comb plate 37 and are provided with keys 38. The rear ends of the key levers are rounded as indicated at 40 to engage half round recesses in links 41 respectively. At the union of the lever ends with the links 41, the parts are slidably 40 confined by the web 25 in the slots 31. The links 41 are slotted as shown at 42, and a pin 43 is passed transversely through the magazine to align and guide the links 41 and limit their movements.

The upper ends of links 41 are 45 rounded and abutted with the lower rounded ends of pawls 44, the abutment between the links and pawls being within the slots 32 of transverse web 26 of the magazine. This web is also comb slotted at its rear to align and guide 50 the stop blades 24 near their lower ends and each stop blade has just above this transverse web a forwardly extending arm 45 having a pin-and-slot connection, as indicated at 46, with each of the pawls 44 respectively.

Pawls 44 are normally biased around the pivot provided by the pin-and-slot connection 46 by springs 47 connected to forwardly extending arms 43 of the pawls and having their other ends anchored to the magazine at 50, the tendency of the springs being to throw forwardly noses 51 at the upper ends of the pawls. Normally this movement is prevented by the pin 50, and the noses 51 are behind a flange 52 of a rocker assembly 53 which includes shaft 54 journaled in ears 55 on the magazine 21. The rocker assembly also includes a body 56 fixed to shaft 54 at 57 and bifurcated to receive a braking member 58 having a forwardly turned flange 60, the main portion of which underlies body 56 and is articulated therewith by a screw 61 passing through a slot 62 in member 56 and threading into the underlying flange 63 of the brake member. A coil spring 63 is interposed between the head of screw 61 and the upper surface of body 56 tending to yieldingly hold the brake member mounted upon the rocker assembly. The brake member 58 has a friction shoe or pad 64 adapted to contact a brake bar 65 fixed by brackets 66 to a traveling paper carriage indicated at 67. This carriage is controlled by escapement mechanism indicated generally at 68 and a spring drum indicated at 70 which actuates the carriage in its letter-spacing and tabulating movements. A conventional platen is indicated at 71 in Fig. 2.

At the end of shaft 54 an arm 72 is keyed to thus function as part of the rocker assembly. At the rear of the arm 72 a strap 73 is secured which leads to a drum 74 mounted on a shaft 75 for transient rotation therewith by clutch means and operating mechanism more fully hereinafter described.

Arm 72 overlies an upturned end of a lever 76 which is pivoted to the frame at 77 and has a forward end carrying a roller 78 which underlies a carriage letter-spacing rack 80 pivoted on the carriage at 81 and urged into engagement with a pinion 82 of the escapement mechanism 68 by a spring 83.

When any one of the denominational tabulator keys 33 is depressed the rear end of its lever 33 will be raised, thus lifting link 41 and consequently lifting the abutting pawl 44. The extent of lift of link 41 is limited by the bottoming of the lever 33 in comb plate 37 and the lift takes up substantially the lost motion provided by pin-and-slot connection 46. Each pawl is recessed at 84 and as a particular pawl is elevated it passes pin 30 until nose 51 escapes the rear edge of flange 52 of the rocker assembly and projects forwardly over the flange, influenced by spring 47. This serves to couple the pawl with the rocker assembly so that when the latter is rocked by application of the power, pawl 44 is further lifted and, by reason of pin-and-slot connection 46, carries with it the associated stop blade 24 thus lifting the upper end of the blade beyond plate 22 into the path of travel of any depressed stop of a series of stops 85 on the carriage. As the rocker assembly is moved by the power, arm 72 swing downwardly until a pin 86 on the arm passes below a shoulder 87 on a latch 88 pivoted at 90 on the rack. The latch influenced by spring 91 moves over pin 86 and holds the rocker temporarily in the position to which it has been moved by the power. Thus stop blade 24 is held lifted in stop position against the action of a return spring 89 anchored on the frame.

Each link 41 has a shoulder 92 near its low extremity and the shoulders underlie a cross bar

93 of a bail 94, pivoted at 95 on the magazine 21. A torsion spring 96 having one end around the forward arm of bail 94 and its other end reacting against the magazine urges the bail downwardly and serves as a return spring for any elevated link 41 and accordingly any depressed lever 33, upon release of the key. An upper arm 97 of bail 94 engages a yoke 98 of a clutch operating element 100 pivoted on the magazine and including a fork 101 positioned between flanges 102 and 103 (see Figs. 4 and 5) of a clutch element 104 slidably mounted on shaft 75 by pins 105 extending from a collar 106 fixed on the shaft 75.

As any link 41 is raised, bail 94 moves clutch part 104 axially to bring clutch teeth 107 into position to engage with clutch teeth 108 of a complementary clutch part 110. This clutch part is normally rotatively loose upon the shaft 75 and includes a sleeve 111 having a flange 112 upon which are formed the engaging teeth 108. The opposite end of sleeve 111 is threaded as indicated at 113 and has threaded thereon a cup 114 and a lock nut 115. Within the cup there is disposed a coil spring 116, bearing against a disk 117 loose on the sleeve, and reacting on the end wall of the cup. Thus adjustment of the cup along the threads of the sleeve increases or decreases the pressure applied on disk 117. A drum 118 is mounted loosely upon the sleeve 111 but is held against axial movement by a member 120 introduced between flanges 121 and 122 of the drum. The member 120 is secured to the magazine. Friction plates 123 and 124 are disposed loosely on the sleeve outside the flanges 121 and 122 and between these flanges and the flange 112 of the sleeve and the disk 117 respectively so that when the clutch parts are engaged by movement of clutch part 104 axially, the drum 118 is frictionally rotated from shaft 75 to wind strap 73 and to move the rocker assembly 53 until brake member 58 engages the bar 65 and presses it against a friction pad 125 on a front face of the magazine. As the pressure increases on the rocker 53 and is resisted by engagement of the brake, spring 63 is compressed, parts 56 and 60 are separated slightly as seen in Fig. 7 of the drawings, and thus the compression of the coil spring 63 is effective to maintain a braking friction of the shoe 64 upon bar 65.

Pin 30 limits the upward movement of any of the pawls and when this limit of movement is reached sleeve 111 of clutch part 110 will continue to move and slip rotatively in drum 74 which is now held against rotation.

By the mechanism so far described the tabulating operation is initiated. A stop is set in the path of the carriage, the escapement is released by lifting the rack 80, the carriage is moved by the spring drum 70 and retarded in its movement by the brake shoe 64. Also the parts have been latched in their operated positions by the latch 88.

The carriage is provided with end bracket members 130 and 131 as shown in Fig. 3 of the drawings. A tabulator rack bar 132 is mounted on these end brackets by stud screw and slot connections shown at 133 and 134. The tabulator rack bar 132 is tubular and rectangular in cross section. It mounts the compressible carriage stops 85 and normally this rack bar occupies a position to the left of that shown in Fig. 3, in which the right ends of the slots are against the screws of the connections 133 and 134 being thus held by a spring 135. In Fig. 3, however, a depressed stop 85 has taken place, that is, a depressed stop 85 has encountered an elevated stop blade 24 and the

carriage has continued to travel a short distance while the rack bar 132 has been held. At the rear of the channel bar 132 a latch-release-plate 136 is loosely mounted by stud screws 137 passing through inclined slots 138 in the latch-release bar. Pins 140 and 141 on the carriage end brackets 130 and 131 respectively project opposite the ends of latch-release bar 136 thus preventing any relative longitudinal movement of the latch-release bar and the carriage. Thus when banking takes place and the carriage proceeds beyond the rack bar, studs 137 acting on the edges of slots 138 cam the bar downwardly into the position shown in Fig. 3 where it is effective on pivoted latch member 88 to disengage shoulder 87 from pin 86 on arm 72 of the rocker assembly.

Inasmuch as by the present mechanism it is unnecessary to hold the key lever 33 depressed after the parts have been conditioned for and actuated by the power operation, the usual practice will be to simply lightly tap the key 38 and release it at once after such power operation, in which case link 41 is immediately dropped back to its normal position allowing bail 94 to resume its normal position under the influence of spring 96 and immediately the clutch connection 104 and 110 is broken. Power from the electric motor is no longer needed as the parts have been latched in their operated positions and the work has been transferred to the carriage-spring-drum 70. If the key is operated in this manner the banking of the carriage, releasing the latch, will allow all the other parts to be restored to normal. However, if the key has been held depressed until after the end of the banking operation, the latch 88 will nevertheless be released in the same manner and held released until release of the key permits restoration of all the parts.

Rocker 53 is pulled downward at its forward end by the return spring 47 of pawl 44 and in the final stage of the downward movement of this pawl the cam face provided by recess 84 cams the pawl nose 51 rearwardly to break its overhanging relation with the flange 52 of the rocker.

As in the case of the invention shown and disclosed in the copending application above referred to, an electric motor, here indicated at 150, may be continuously energized to drive the clutch shaft or intermittently energized upon the selection of any denominational tabulator stop. If it is desired to intermittently energize the motor, cross bar 93 is provided with a lip 151 overhanging the end of a contact arm 152 so that as any key is depressed and cross arm 93 is raised the circuit will be closed through 153—154.

In the preferred form of the invention above described and shown in the accompanying drawings, the invention is shown as applied to a typewriter of the standard or impact form. Obviously, however, the invention in its broader aspects may be applied to a typewriter in which the type action operates on the pressure principle and in which typewriters it is customary in manual tabulating to release an escapement dog rather than elevate a letter-space rack and in which friction braking of the carriage-tabulating movement does not usually involve the long brake bar used in the standard typewriters.

What is claimed is:

1. Power-driven denominational tabulator mechanism comprising, a movable carriage having a stop, a motor-driven shaft, a normally open clutch, a frame having a plurality of denominational tabulator stops slidably mounted therein, each tabulator stop having a pivoted spring-urged

pawl, an operating key-lever for each of the pawls of said denominational tabulator stops, links articulated respectively with the key levers and slidably mounted in the frame underlying the said pawls, a pivoted universal clutch-operating member 5 spring-pressed normally to clutch-opening position and adapted to be operated by a selected key-lever to close the clutch, a rocker normally out of the path of the pawls and adapted to be rocked by the drive shaft when the clutch is closed, means on the rocker for engaging a pawl when the latter is operated by a key lever and for moving said pawl to move its associated tabulator stop to operative position, and means for holding the rocker against return until the completion of 15 the tabulating movement but permitting prior opening of the clutch.

2. Power tabulating mechanism comprising a frame, a carriage releasable for resulting tabulating movement, a stop on the frame projectible 20 to carriage-arresting position, a drive shaft, an actuator for projecting said stop, a connection, including a closeable clutch, for moving said actuator by said shaft from a normal position to a stop-projecting position, a tabulating key, means 25 operatively connecting said stop to said actuator in response to operation of said key, means controlled by operation and return of said key to close and reopen said clutch, the moved actuator and the thereby projected stop tending to return 30 to said normal position if said clutch is reopened, means for holding said actuator in moved position irrespective of release of said key and reopening of said clutch before encounter of said carriage with said stop, carriage-releasing means operable 35 in conjunction with the projecting of said stop being provided, and means responsive to said encounter to release said actuator from said holding means for consequent restoration of said actuator and stop. 40

3. Power tabulating mechanism comprising a frame, a carriage releasable for resulting tabulating movement, a stop on the frame projectible to carriage-arresting position, a drive shaft, an actuator for projecting said stop, a connection, 45 including a closeable clutch, for moving said actuator by said shaft from a normal position to a stop-projecting position, a tabulating key, means operatively connecting said stop to said actuator in response to operation of said key, means controlled by operation and return of said key to 50 close and reopen said clutch, the moved actuator and the thereby projected stop tending to return to said normal position if said clutch is reopened, means for holding said actuator in moved position irrespective of release of said key and reopening of said clutch before encounter of said carriage with said stop, carriage-releasing means operable 55 in conjunction with the projecting of said stop being provided, and means responsive to said encounter to release said actuator from said holding means for consequent restoration of said actuator and stop, said connection including a slip-friction device providing for overrunning of the drive shaft when the actuator has been 60 moved to stop-projecting position. 65

4. Power tabulating mechanism comprising a carriage releasable for resulting tabulating movement, a frame having a stop projectible to carriage-arresting position, a motor, a rocker for 70 projecting said stop, a tabulating key, a pawl moved in response to operation of said key to connect said stop and rocker, means, including a clutch held normally open by a spring and closeable by said key operation, for moving the 75

rocker by said motor to project said stop, said clutch reopening in response to return of said key and said rocker and stop tending to return in response to reopening of said clutch, means 5 for holding said rocker in moved position irrespective of return of said key and the reopening of said clutch, before encounter of the carriage with said stop, carriage releasing means operable in conjunction with the projecting of said 10 stop being provided, and means responsive to said encounter to disengage said rocker from said holding means for consequent restoration of said rocker and stop.

5. Power tabulating mechanism comprising a 15 carriage releasable for resulting tabulating movement, a frame having a stop projectible to carriage-arresting position, a motor, a rocker for projecting said stop, a tabulating key, a pawl moved in response to operation of said key to 20 connect said stop and rocker, means, including a clutch held normally open by a spring and closeable by said key operation, for moving the rocker by said motor to project said stop, said clutch reopening in response to return of said 25 key and said rocker and stop tending to return in response to reopening of said clutch, means for holding said rocker in its stop-projecting position so as to permit return of said key, and the attendant reopening of said clutch as soon 30 as said stop is projected, and means responsive to encounter of said carriage with said stop to release said rocker from said holding means for consequent restoration of said rocker and stop, carriage-releasing means operable in conjunction 35 with the projecting of said stop being provided.

6. Power tabulating mechanism comprising a carriage releasable for resulting tabulating movement, a frame having a stop projectible to carriage-arresting position, a motor, a rocker for 40 projecting said stop, a tabulating key, means operatively connecting said stop to said rocker in response to operation of said key, means, including a clutch closeable by said key operation for moving the rocker by the motor to project 45 said stop, said clutch reopening in response to return of said key and said rocker and stop tending to return in response to reopening of said clutch, means for holding said rocker in moved position irrespective of return of said key 50 and the reopening of said clutch before the encounter of the carriage with said stop, carriage-releasing means operable in conjunction with the projecting of the stop being provided, a spring-influenced member, for braking the 55 tabulating movement of the carriage, set in operative position by the power movement of said rocker and maintained under carriage-braking spring pressure by the holding of said rocker in moved position by said holding means, and means 60 responsive to the encounter of the carriage with the stop to release said rocker from said holding means for consequent return of said rocker and stop and release of said braking means.

7. Power tabulating mechanism comprising a 65 carriage, releasable for resulting tabulating movement, a frame having a plurality of stops projectible individually to carriage-arresting position, a universal stop-projector movable from a normal position to a stop-projecting position, 70 projector-engaging elements mounted respectively on the stops, a motor driven shaft, means, including a normally open clutch, for moving the projector by said motor driven shaft, key-means

operable to selectively condition said engaging elements for movement by said projector, means operable by said key-means to close said clutch so that said shaft moves said projector to move the selected engaging element to project the 5 corresponding stop, said clutch becoming reopened in response to return of said key-means and said projector and stop tending to return in response to the reopening of the clutch, means for latching the projector in the stop-projecting 10 position to which it is moved by said shaft, carriage releasing means operable in conjunction with projecting said stop, and means operable automatically under control of the carriage, substantially at the end of its tabulating movement, 15 for releasing said projector from said latching means.

8. Power tabulating mechanism comprising a carriage releasable for resulting tabulating movement, a frame having a stop projectible from 20 retracted position to carriage-arresting position, a motor-driven shaft, a key, means responsive to depression of said key to cause said shaft to transmit a stop-projecting force to said stop and incidentally to tend to sustain the consequently 25 projected stop by said force only so long as said key is kept depressed, wherefore said stop tends to return to normal position in response to return of said key, carriage-releasing means operable in conjunction with the projecting of said 30 stop, and means automatically effective, aside from said force, for holding the stop in projected position, to thus allow for the immediate release of the key upon initiation of the tabulating movement of the carriage, provision being made where- 35 by said carriage is effective substantially at the end of its tabulating movement to release said stop from said holding means.

9. Power driven denominational tabulator mechanism comprising, a spring-motored escapement-controlled carriage having a stop, a motor-driven shaft, a clutch spring-pressed to normally 40 open position, a frame having a plurality of denominational tabulator-stops and a rocker, rocker-moving means connectible to said shaft by 45 said clutch, each tabulator stop having a spring-pressed rocker-engaging member normally held out of spring-urged engagement with the rocker, means controlled by the movement of said rocker to release the carriage from the escapement- 50 control for resulting tabulating movement of the carriage, denominational tabulator keys operatively connected to said rocker-engaging members so that operation of any one of said keys determines engagement of a corresponding member with the rocker, means operable by any one 55 of said keys to close the clutch to enable the shaft and rocker-moving means to move the rocker to project a corresponding tabulator-stop to carriage-arresting position, a latch spring-urged into position to hold the rocker in the position to which it is moved by the shaft, and a latch-releasing member operative in response to 60 encounter of the carriage with the projected denominational-stop to release said latch, said rocker and the projected stop tending to return upon said release of the latch, the arrangement being such that said key may be released before 65 said encounter and that said clutch will reopen in response to release of said key before said 70 encounter.

WILLIAM F. HELMOND.
